UNITED STATES PATENT OFFICE.

FRANK CONRAD, OF SWISSVALE, PENNSYLVANIA, ASSIGNOR TO WESTINGHOUSE ELECTRIC AND MANUFACTURING COMPANY, A CORPORATION OF PENNSYLVANIA.

GEAR.

1,167,743.

Specification of Letters Patent.

Patented Jan. 11, 1916.

Original application filed July 2, 1913, Serial No. 776,951. Divided and this application filed April 6, 1915. Serial No. 19,608.

To all whom it may concern:

Be it known that I, FRANK CONRAD, a citizen of the United States, and a resident of Swissvale, in the county of Allegheny and State of Pennsylvania, have invented a new and useful Improvement in Gears, of which the following is a specification, this application being a division of application, Serial No. 776,951, filed July 2, 1913.

10 My invention relates to non-metallic gear wheels and pinions, and it has for its object to provide such devices which shall be light, strong and durable in construction and noiseless in operation.

15 Gear wheels and pinions (which, for convenience, will hereinafter be designated as gears) have heretofore been constructed of non-metallic metals, but such gears have usually been unsuited for service where

20 strength and long life are required, on account of the low tensile strength of the materials heretofore employed. Certain types of non-metallic gears, such as those composed of laminations of rawhide and the

25 like, have the further disadvantages that they are but slightly resistant to heat and readily absorb moisture and oils, and these properties greatly restrict the field of usefulness of such gears. Another mechanical

30 disadvantage of the non-metallic gears that have heretofore been made is that such gears have usually been made up of a number of laminations of the non-metallic material firmly compressed between metallic end

35 plates which increase the thickness of the gear but are useless in transmitting power.

According to my invention, as set forth in my copending application Serial No. 776,951, filed July 2, 1913, of which this ap-

40 plication is a division, I construct integral gears of a composite material consisting of fibrous material such as paper, cloth and the like combined with an adhesive liquid material, preferably a phenolic condensation

45 product, such as bakelite, which is a condensation product of phenols and formaldehyde. My present application relates to that species of my invention according to which gears are made of cloth fabrics such as duck, muslin and the like, united, as heretofore stated, by means of an adhesive.

50 One embodiment of my invention is illustrated in the accompanying drawing in which—

Figure 1 is an end view of a spur gear 55 constructed in accordance with my invention and Fig. 2 is a diametral sectional view of the gear shown in Fig. 1.

The gear shown in the drawing is an ordinary spur gear having a body 1, teeth 2 and 60 a central opening or bore 3.

The material of which the gear is constructed is preferably made by coating cotton duck or other suitable cloth fabric with bakelite or other similar adhesive. The adhesive is applied in liquid form and the cloth may then be dried by passing it over a series of rollers in a heated oven. The prepared cloth is then cut into sheets of a convenient size, which are stacked one upon 70 another with the treated side of each sheet next to the untreated side of the adjacent sheet until a sufficient number of sheets have been superposed to produce a plate of the required thickness. The stack of sheets is 75 then placed between metal plates and the assembled structure is pressed between the heated platens of a hydraulic press. Pressure and heat are applied to a degree which may be varied in accordance with the adhesive employed and the thickness of the composite plate. The effect of this heat treatment under pressure is to firmly cement together the sheets of cloth and to further impregnate the cloth with the adhesive. The 80 plate is transformed into a hard, compact and coherent mass. After cooling, the composite material is removed from the press and clamped between steel plates to prevent warping during baking, which is the 85 last step in the process, and which is performed in heated ovens. The composite plates are allowed to remain in the baking ovens for several hours, during which time any moisture that may be present is expelled 90 and the bakelite is transformed into its solid, infusible and insoluble condition. The plates are then removed from the oven and the finished product is allowed to cool. The resulting material has substantially the 95 physical properties set forth in the application of which the present application is a division. The specific material to which my present application relates is superior to that composed of paper and bakelite or 100 similar adhesive in tensile strength and in elasticity, and gears composed of cloth and bakelite are therefore able to withstand

105

heavier service than gears composed of paper and bakelite. The finished plates of composite material are cut into blanks of any desired size and the gear teeth are cut in any usual or convenient manner.

5 The form of gear shown in the accompanying drawing is merely illustrative, and materials made according to my invention may be used for making gears of any desired kinds, sizes and proportions. It is to be understood that my invention comprehends all such modifications and changes in materials as fall within the scope of the appended claims.

10 15 I claim as my invention:

1. A gear having a self-sustaining working body portion composed of laminations of cloth cemented together by means of an adhesive.

20 2. A gear having a self-sustaining working body portion composed of laminations

of cloth cemented together by means of an adhesive that resists attack by heat, oil or water, under operating conditions.

3. A gear having a self-sustaining working body portion composed of laminations of cloth and a phenolic condensation product.

25 4. A gear having a self-sustaining working body portion composed of laminations of cloth and a binder that resists attack by heat, oil or water under operating conditions.

30 35 5. A gear having a self-sustaining working body portion composed of laminations of cloth and a binder that is unimpaired by operating temperatures.

In testimony whereof, I have hereunto subscribed my name this 30th day of March, 1915.

FRANK CONRAD.
